UNITED STATES PATENT OFFICE

161,358

MEMO PAD HOLDER

Gordon B. Miller, Glendale, Ohio, assignor to Gordon B. Miller & Company, Cincinnati, Ohio, a company of Ohio

Application March 22, 1949, Serial No. 1,518

Term of patent 14 years

(Cl. D74—1)

To all whom it may concern:

Be it known that I, Gordon B. Miller, a citizen of the United States, residing at Glendale, in the county of Hamilton, and State of Ohio, have invented a new, original, and ornamental Design for a Memo Pad Holder, of which the following is a specification, reference being had to the accompanying drawings, forming a part thereof.

Figure 1 is a perspective view of the memo pad holder showing my new design. The two sides of the holder are substantially the same.

I claim:

The ornamental design for a memo pad holder substantially as shown and described.

GORDON B. MILLER.
